UNITED STATES PATENT OFFICE.

JAMES M. BERRY, OF DETROIT, MICHIGAN.

CURTAIN-ROLLER CAP.

No. 853,622.

Specification of Letters Patent.

Patented May 14, 1907.

Application filed February 23, 1906. Serial No. 302,608.

To all whom it may concern:

Be it known that I, JAMES M. BERRY, a citizen of the United States of America, residing at Detroit, in the county of Wayne and State of Michigan, have invented certain new and useful Improvements in Curtain-Roller Caps, of which the following is a specification, reference being had therein to the accompanying drawings.

10 The invention relates generally to spring curtain rollers, and particularly to a cap, the pawls of which are adapted to be held at will in inoperative position.

15 It is frequently desirable to use a curtain roller at the sides or lower end of a window, for the purpose of being drawn transversely or upwardly by means of a cord passing over suitable sheaves or pulleys. In these instances, in order that the curtain may be 20 readily raised and lowered, it is necessary that the pawls be inoperative.

The present invention is designed to permit of the retention of the pawls in inoperative positions, and also to allow the use of 25 the roller in the ordinary manner, and it consists in the novel construction of the cap, and in the peculiar arrangement and combination of the parts, as will be more fully herein-after set forth.

30 In the drawings illustrating the invention, Figure 1 is a view in perspective of a curtain roller and cap of ordinary construction, the cap being partly in section; Fig. 2 is a detached perspective view of the cylindrical cap body; Fig. 3 is a view showing a modified form of cap; Fig. 4 is a further modification; and Fig. 5 is a detached perspective view of the overlying plate forming a part of the cap shown in Fig. 4.

40 In the drawings thus described, A represents the usual curtain roller, recessed in the ordinary manner at its upper end; C is a cylindrical body portion of the cap, D is the usual end plate, driven within the end of the 45 roller by suitable lugs, as a.

E represents the pawls, pivoted upon the plate D, and F a spring ratchet which the pawls engage. In this instance the retaining means for the pawls consists of lugs or fingers

50 H, formed of integral portions of the cylin-

drical cap body, C. They are normally in the position shown in Fig. 2, extending in the plane of the inturned marginal flange I. When it is desired to render the pawl inoperative, these fingers are depressed, in the manner indicated at b in Fig. 1, to engage the pawl and hold it out of engagement with the ratchet F. When it is desired to use the roller again in the ordinary manner, the fingers or lugs are merely bent outwardly into 60 their normal position, and the pawls are again free to operate in the ordinary manner.

In Fig. 3 a modified form of cap is shown, its end plate J in this instance being formed preferably integral with the cylindrical body 65 section K. Retaining lugs or ears L are formed from integral portions of the plate J, the latter being properly cut or slotted so as to permit of the projecting portions being extended upwardly when desired to engage 70 the pawls, as illustrated.

In Fig. 4 a further modification is shown, wherein the retaining ears M are upon an auxiliary plate O, adapted to be mounted upon any ordinary end plate of a roller and held thereon by means of the pawl pivots P. The ears M, as shown in Fig. 5, are struck from the auxiliary plate, and are adapted to be bent downwardly into engagement with the pawls when the latter are to be held 80 from engagement with the ratchet.

It will be observed that the pawl-retaining devices are in each instance adjustable to be brought into or out of operative relation with the pawls, as may be desired, thus 85 adapting the ordinary curtain roller, at little if any additional expense, for either ordinary use or to be used at the bottom of the window or at the side, as preferred.

What I claim is,—

1. In a curtain roller cap, the combination 90 with the end plate, pawls pivoted thereon, an auxiliary plate rigidly secured to said end plate, and fingers or lugs formed of integral portions of said latter plate, adapted to be 95 extended into engagement with the pawls.

2. A curtain roller cap, comprising an end plate, pawls pivoted thereon, and an auxiliary plate rigidly secured to said end plate and slit to form pliable tongues normally 100

in the plane of said auxiliary plate and arranged to be bent into engagement with said pawls, for the purpose described.

3. In a curtain roller cap, the combination with the cap proper and the pivoted pawls therefor, of pliable tongues having their bases rigidly connected to the cap proper and their ends arranged to be bent into op-

erative relation to the pawls, for the purpose described.

In testimony whereof I affix my signature in presence of two witnesses.

JAMES M. BERRY.
